United States Patent Office

Des. 197,034
Patented Dec. 3, 1963

197,034

BOAT

Albert W. Lofé, 67 Eglin St., Fort Walton Beach, Fla.

Filed Mar. 15, 1962, Ser. No. 69,285

Term of patent 14 years

(Cl. D71—1)

FIG. 1.

FIG. 2.

FIG. 3.

FIG. 4.

FIG. 5.

FIG. 7.

FIG. 6.

FIG. 1 is a top plan view of a boat showing my new design;

FIG. 2 is a side elevation view thereof as seen from the left side of FIG. 1;

FIG. 3 is a bottom plan view thereof;

FIG. 4 is a front elevation view thereof;

FIG. 5 is a rear elevation view thereof;

FIG. 6 is a front perspective view thereof; and

FIG. 7 is a perspective view taken from the rear of the boat.

I claim:

The ornamental design for a boat, as shown.
